Patented Mar. 14, 1922

FIG. 1.

FIG. 2.

Inventor:
Wilhelm Schimmel
Attorney: A. H. Hadden

UNITED STATES PATENT OFFICE.

WILHELM SCHIMMEL, OF LEIPZIG-STOTTERITZ, GERMANY.

MECHANICAL HAND.

1,409,415.

Specification of Letters Patent. Patented Mar. 14, 1922.

Application filed May 3, 1921. Serial No. 466,526.

(GRANTED UNDER THE PROVISIONS OF THE ACT OF MARCH 3, 1921, 41 STAT. L., 1313.)

To all whom it may concern:

Be it known that I, WILHELM SCHIMMEL, of Leipzig-Stotteritz, Germany, a citizen of the German Republic, have invented certain 5 new and useful Improvements in Mechanical Hands, (for which I have filed an application in Germany, June 6, 1919,) of which the following is a specification.

The object of this invention is to provide 10 a mechanical hand which is adapted to play key instruments of any kind and can conveniently be used for advertising purposes, as by placing the same in a shop window together with a piano, which it plays.

15 The invention is illustrated in the annexed drawing.

Fig. 1 is a sectional view with the hand closed.

20 Fig. 2 is a full view of the hand with partially closed fingers.

In the drawing, *a* designates part of the arm or wrist, *b* the hand, and *c* a frame or holder. The fingers *f* pivoted to the hand are in the form of bell cranks, whose arms 25 *d* are connected by wires *z* or equivalent means to levers *g* pivoted to the frame *c*. The levers *g* are held by springs *l* in contact with cams *m* on a shaft *n*, which is driven by an electromotor, spring motor, or equivalent means, so that the cams *m* actuate the 30 levers *g* in turn and thus cause the fingers to strike the keys of the instrument over whose

keyboard they are placed, the action being very similar to that of a natural hand. There may, of course, be two hands, joined 35 to a figure seated on a chair. Means for moving the arms laterally may be provided, but are not included in this invention.

What I claim as my invention and desire to secure by Letters Patent of the United 40 States is:—

1. A mechanical hand for playing key instruments, comprising a support, fingers pivoted to said support, a shaft, a series of cams on said shaft, and means whereby said 45 cams severally actuate said fingers.

2. A mechanical hand for playing key instruments, comprising a support, fingers pivoted to said support, a shaft, a series of cams on said shaft, a series of levers severally 50 actuated by said cams, and means severally connecting said levers to said fingers.

3. A mechanical hand for playing key instruments, comprising a support, fingers pivoted to said support, a shaft, a series of cams 55 on said shaft, a series of levers severally actuated by said cams, and wires severally connecting said levers to said fingers.

In witness whereof I have signed this specification in the presence of two witnesses. 60

WILHELM SCHIMMEL.

Witnesses:

LUISE TSCHERNY,
ARTHUR WERNER.
